Primary Examiner — Michelle E. Wilson*Assistant Examiner* — Messina L Smith(74) *Attorney, Agent, or Firm* — Caseiro Burke LLC;
Chris A. Caseiro(57) **CLAIM**

The ornamental design for an attachment for a comb, as shown and described.

DESCRIPTION

FIG. 1 is a perspective view of an attachment for a comb showing our new design;

FIG. 2 is another perspective view thereof;

FIG. 3 is a front view thereof;

FIG. 4 is a back view thereof;

FIG. 5 is a top view thereof;

FIG. 6 is a bottom view thereof; and,

FIG. 7 is a side view thereof.
